PORTABLE SAFE

Ralph M. Ferguson, Dayton, Ohio

Application September 22, 1944, Serial No. 555,383

4 Claims. (Cl. 109—25)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to portable safes for storing secret and confidential papers and other documents.

One of the objects of this invention is to provide a portable safe which is preferably in the form of a water-proof armoring housing, adapted to carry and protect confidential and valuable papers and documents, and especially papers that contain secret military data.

A more particular object of this invention is to provide a water-proof and fire-proof safe for carrying papers and documents, which safe is furthermore arranged to carry a destroying medium which is adapted to be readily released so as to destroy said papers or obliterate the same, whenever that may become desirable, whereby this safe is particularly useful for carrying secret military papers and the like by airplane over enemy territory, and is readily operable to destroy the papers and prevent them from falling intact into the hands of an enemy.

These and various other objects and advantages are attained with this invention, as will become apparent from the following description, taken in connection with the accompanying drawing wherein the invention is shown in its preferred form, it being evident that other arrangements and forms of construction may be resorted to for carrying out the objects and purposes of this invention.

The figure in the drawing is a perspective view illustrating an embodiment of this invention in its preferred form of construction.

This invention in its preferred form, as disclosed in the drawing, comprises an outer container 6 which constitutes a housing, and an inner container or receptacle 7 which is mounted therein and is arranged and adapted for carrying confidential papers and other documents.

The housing 6 is preferably constructed in the form of a laminated armoring container and is made cylindrical in shape, comprising a tubular outer wall 8 and inner wall 9 of steel, with a wall 10 of asbestos or other fire-proof material therebetween, a steel ring 11 being positioned at each end of the tubular asbestos member 10. A closure member 12 is secured to one end of the tubular housing for closing said end, and a closure member or cap 13 is mounted fluid-tight but openably over the other end of the housing. Said cap may also be provided with locking

means 14 and a handle 15 for carrying.

Means 16 is provided for admitting fluid into the housing 6.

Means 17 is provided for admitting fluid into the inner container 7.

Means 18 is provided for admitting fluid into the chamber 16.

Means 19 is provided for admitting fluid into the chamber 16.

Means 20 is provided for admitting fluid into the chamber 16.

Means 21 is provided for admitting fluid into the chamber 16.

Means 22 is provided for admitting fluid into the chamber 16.

Means 23 is provided for admitting fluid into the chamber 16.

Means 24 is provided for admitting fluid into the chamber 16.

Means 25 is provided for admitting fluid into the chamber 16.

Means 26 is provided for admitting fluid into the chamber 16.

Means 27 is provided for admitting fluid into the chamber 16.

Means 28 is provided for admitting fluid into the chamber 16.

Means 29 is provided for admitting fluid into the chamber 16.

Means 30 is provided for admitting fluid into the chamber 16.

Means 31 is provided for admitting fluid into the chamber 16.

Means 32 is provided for admitting fluid into the chamber 16.

Means 33 is provided for admitting fluid into the chamber 16.

Means 34 is provided for admitting fluid into the chamber 16.

Means 35 is provided for admitting fluid into the chamber 16.

Means 36 is provided for admitting fluid into the chamber 16.

Means 37 is provided for admitting fluid into the chamber 16.

Means 38 is provided for admitting fluid into the chamber 16.

Means 39 is provided for admitting fluid into the chamber 16.

Means 40 is provided for admitting fluid into the chamber 16.

Means 41 is provided for admitting fluid into the chamber 16.

Means 42 is provided for admitting fluid into the chamber 16.

Means 43 is provided for admitting fluid into the chamber 16.

Means 44 is provided for admitting fluid into the chamber 16.

Means 45 is provided for admitting fluid into the chamber 16.

Means 46 is provided for admitting fluid into the chamber 16.

Means 47 is provided for admitting fluid into the chamber 16.

Means 48 is provided for admitting fluid into the chamber 16.

Means 49 is provided for admitting fluid into the chamber 16.

Means 50 is provided for admitting fluid into the chamber 16.

Means 51 is provided for admitting fluid into the chamber 16.

Means 52 is provided for admitting fluid into the chamber 16.

Means 53 is provided for admitting fluid into the chamber 16.

Means 54 is provided for admitting fluid into the chamber 16.

Means 55 is provided for admitting fluid into the chamber 16.

Means 56 is provided for admitting fluid into the chamber 16.

Means 57 is provided for admitting fluid into the chamber 16.

Means 58 is provided for admitting fluid into the chamber 16.

Means 59 is provided for admitting fluid into the chamber 16.

Means 60 is provided for admitting fluid into the chamber 16.

Means 61 is provided for admitting fluid into the chamber 16.

Means 62 is provided for admitting fluid into the chamber 16.

Means 63 is provided for admitting fluid into the chamber 16.

Means 64 is provided for admitting fluid into the chamber 16.

Means 65 is provided for admitting fluid into the chamber 16.

Means 66 is provided for admitting fluid into the chamber 16.

Means 67 is provided for admitting fluid into the chamber 16.

Means 68 is provided for admitting fluid into the chamber 16.

Means 69 is provided for admitting fluid into the chamber 16.

Means 70 is provided for admitting fluid into the chamber 16.

Means 71 is provided for admitting fluid into the chamber 16.

Means 72 is provided for admitting fluid into the chamber 16.

Means 73 is provided for admitting fluid into the chamber 16.

Means 74 is provided for admitting fluid into the chamber 16.

Means 75 is provided for admitting fluid into the chamber 16.

Means 76 is provided for admitting fluid into the chamber 16.

Means 77 is provided for admitting fluid into the chamber 16.

Means 78 is provided for admitting fluid into the chamber 16.

Means 79 is provided for admitting fluid into the chamber 16.

Means 80 is provided for admitting fluid into the chamber 16.

Means 81 is provided for admitting fluid into the chamber 16.

Means 82 is provided for admitting fluid into the chamber 16.

Means 83 is provided for admitting fluid into the chamber 16.

Means 84 is provided for admitting fluid into the chamber 16.

Means 85 is provided for admitting fluid into the chamber 16.

Means 86 is provided for admitting fluid into the chamber 16.

Means 87 is provided for admitting fluid into the chamber 16.

Means 88 is provided for admitting fluid into the chamber 16.

Means 89 is provided for admitting fluid into the chamber 16.

Means 90 is provided for admitting fluid into the chamber 16.

Means 91 is provided for admitting fluid into the chamber 16.

Means 92 is provided for admitting fluid into the chamber 16.

Means 93 is provided for admitting fluid into the chamber 16.

Means 94 is provided for admitting fluid into the chamber 16.

Means 95 is provided for admitting fluid into the chamber 16.

Means 96 is provided for admitting fluid into the chamber 16.

Means 97 is provided for admitting fluid into the chamber 16.

Means 98 is provided for admitting fluid into the chamber 16.

Means 99 is provided for admitting fluid into the chamber 16.

Means 100 is provided for admitting fluid into the chamber 16.

Means 101 is provided for admitting fluid into the chamber 16.

Means 102 is provided for admitting fluid into the chamber 16.

Means 103 is provided for admitting fluid into the chamber 16.

Means 104 is provided for admitting fluid into the chamber 16.

Means 105 is provided for admitting fluid into the chamber 16.

Means 106 is provided for admitting fluid into the chamber 16.

Means 107 is provided for admitting fluid into the chamber 16.

Means 108 is provided for admitting fluid into the chamber 16.

Means 109 is provided for admitting fluid into the chamber 16.

Means 110 is provided for admitting fluid into the chamber 16.

Means 111 is provided for admitting fluid into the chamber 16.

Means 112 is provided for admitting fluid into the chamber 16.

Means 113 is provided for admitting fluid into the chamber 16.

Means 114 is provided for admitting fluid into the chamber 16.

Means 115 is provided for admitting fluid into the chamber 16.

Means 116 is provided for admitting fluid into the chamber 16.

Means 117 is provided for admitting fluid into the chamber 16.

Means 118 is provided for admitting fluid into the chamber 16.

Means 204 is provided for admitting fluid into the chamber 16.

Means 205 is provided for admitting fluid into the chamber 16.

Means 206 is provided for admitting fluid into the chamber 16.

Means 207 is provided for admitting fluid into the chamber 16.

Means 208 is provided for admitting fluid into the chamber 16.

Means 209 is provided for admitting fluid into the chamber 16.

Means 210 is provided for admitting fluid into the chamber 16.

Means 211 is provided for admitting fluid into the chamber 16.

Means 212 is provided for admitting fluid into the chamber 16.

Means 213 is provided for admitting fluid into the chamber 16.

Means 214 is provided for admitting fluid into the chamber 16.

Means 215 is provided for admitting fluid into the chamber 16.

Means 216 is provided for admitting fluid into the chamber 16.

Means 217 is provided for admitting fluid into the chamber 16.

Means 218 is provided for admitting fluid into the chamber 16.

safety means, so as to prevent the stem from being unintentionally drawn out to accidentally rupture the container.

It should be noted that this safe is especially suitable for storing valuable papers and is of a size to be conveniently carried in a traveling bag or in a lady's hand bag, and the like, as well as being carried in a suitable location in an airplane; and furthermore that it is particularly arranged and adapted for safely carrying military papers of a secret nature therein, even over enemy territory, and can be readily manipulated for actuating a destroying medium so as to enter the otherwise safe container and destroy the papers and documents therein to prevent them from falling into the hands of an enemy.

I claim:

1. A safe composed of a housing having an openable closure member thereon, a container in the housing for receiving confidential papers therein, a chamber provided between the exterior of the container and the interior of the housing to receive a medium capable of destroying the papers, said container being of a material capable of resisting the destructive action of said medium, and rupturing means including a stem having its inner end secured in the container and being readily operable from the exterior of the housing, whereby to pull said stem and the attached part of the container and rupture the latter to admit said medium thereinto for destroying the papers.

2. A safe comprising a housing, a container in the housing for receiving confidential papers therein, a chamber provided between the exterior of the container and the interior of the housing to receive a fluid capable of destroying the papers, said container being of a material capable of resisting the destructive action of said fluid,

an element secured to the container and being readily operable from the exterior of the housing, for moving said element and the attached part of the container and thereby rupture the container to admit the fluid thereinto for destroying the papers, and cooperating safety means on the element and on the housing being rotatably engaged and thereby preventing the element from being unintentionally actuated to rupture the container.

3. A safe comprising a liquid-proof armoring housing having a locking cap thereon, a liquid-proof container in the housing for receiving and storing documents therein, a chamber provided between the container and the housing for receiving a corrosive acid therein, said container being of an acid resisting material, a stem having its inner end connected with the container and projecting through the housing, rupturing means wherewith the stem cooperates, and means for readily operating the stem for rupturing the container and admitting the acid to the documents therein for destroying the same.

4. A safe comprising a liquid-proof tubular housing having openable closure means thereon, a bag of pliable liquid-proof material in the housing for containing confidential papers therein, a chamber provided between the exterior of said bag and the interior of the housing for receiving a corrosive liquid capable of destroying the papers, and means including a stem and also cooperating rupturing means in the housing, said stem being attached to the bag and being readily operable from the exterior of the housing, whereby to move the bag against said means to rupture the bag and admit the liquid thereinto for destroying the papers therein.
